UNITED STATES PATENT OFFICE.

CROSBY FIELD, OF BROOKLYN, NEW YORK, ASSIGNOR TO CHEMICAL MACHINERY CORPORATION, OF NEW YORK, N. Y.

DRYING PROCESS AND APPARATUS THEREFOR.

1,358,431.

Specification of Letters Patent.

Patented Nov. 9, 1920.

Application filed December 8, 1917. Serial No. 206,198.

To all whom it may concern:

Be it known that I, CROSBY FIELD, a citizen of the United States, and resident of the borough of Brooklyn, city, county, and State of New York, have invented certain new and useful Improvements in Drying Processes and Apparatus Therefor, of which the following is a specification.

The present invention relates to an improved drying process and apparatus therefor, particularly for use in the drying of chemicals, such as organic salts for colors, dyes, or the like, which prior to drying are in a plastic or semi-liquid state.

Heretofore, drying processes in which a vacuum has been employed, have been intermittent in their operation, which resulted in numerous disadvantages and a non-uniform drying, which obviously tended to the production of an inferior product.

Furthermore, the apparatus was cumbersome, complicated, and slow in operation, and did not permit of interchangeability, that is, in drying dyes, one apparatus could only be used for one color without expensive cleaning.

It is an object of the present invention, therefore, to obviate these difficulties and to provide a continuous drier in which a vacuum may be maintained, and it is also an object to produce an apparatus of such simplicity that numerous such apparatuses may be installed, consistent with economy, and at the same time I propose that each apparatus may by slight interchangeability of certain of its elements, be adapted to the drying of various colors successively, that is, after one color is dried the change in the apparatus is made and thereupon another color may be dried.

To this end, I propose to provide in the present embodiment of my invention a squirting action, whereby the wet or plastic dye or chemical may be squirted through a nozzle or orifice, upon a continuously moving endless apron, the material being squirted in a thin film over a large area or in a plurality of streams, so that a quick drying action results.

I also propose to provide an air tight tunnel or chamber for housing the conveyer apron, in which the atmospheric condition may be controlled, it being possible to maintain an air pressure either above or below atmosphere, or the atmosphere may be sat-

urated to any desired degree by water of evaporation, or an atmosphere of gas, or any other desirable composition may be introduced. An object is to provide in connection with the drying chamber an improved heating jacket which may be supplied with hot water, steam, oil, or other suitable heating means.

Under certain conditions the material is in such a moist state that it is desirable to extract the excess moisture before introducing the material into the drying chamber, so that it is a further object of the invention to provide means for automatically removing the desired amount of moisture before squirting the material into the chamber.

A still further object is to provide a conveyer frame, which may be readily removed from the drying chamber, and in connection therewith a conveyer apron which effectually supports and retains the material during the drying process and delivers the same therefrom when dried.

With these and other objects in view an embodiment of my invention is shown in the accompanying drawings, and the process and apparatus will be hereinafter more fully described with reference thereto, and the invention will be finally pointed out in the claims.

In the accompanying drawings;

Fig. 1 is a vertical longitudinally sectional view of the apparatus;

Fig. 2 is a vertical transverse sectional view along the line 2—2 of Fig. 1;

Fig. 3 is a horizontal section of the driving and delivery end of the drier;

Fig. 4 is a horizontal sectional view taken along the line 4—4 of Fig. 1 of the feed end;

Fig. 5 is a sectional view of the squirting nozzle showing a single elongated orifice;

Fig. 6 is a similar view of a modified nozzle having a plurality of orifices;

Fig. 7 is a horizontal sectional view similar to Fig. 4 and showing the filter attachment in place;

Fig. 8 is a vertical sectional view along the line 8—8 of Fig. 7;

Fig. 9 is an elongated plan view of a portion of the filter attachment showing the surface formation;

Fig. 10 is a vertical sectional view thereof;

Fig. 11 is a vertical sectional view of a modified form of press; and

Fig. 12 is a vertical sectional view with

parts broken away, showing the manner of maintaining a vacuum in the drying chamber.

Similar reference characters indicate corresponding parts throughout the several figures of the drawings.

Referring to the drawings, the embodiment shown by way of example therein, for carrying out my invention, comprises a press 10 at one end, consisting of a cylinder 20 in the bore 21 of which there is slidably mounted a plunger shaft 22 provided at its upper end with a piston head 23 disposed in a double acting pump, or motor 24, mounted above the cylinder upon a pair of standards 25 and 26, the lower flanged ends 27 of the said standards being bolted as at 28 to a lateral flange 29 at the upper end of the cylinder 20. A lateral port or feed opening 20^a is 15 provided in the cylinder below the top of the stroke of the plunger indicated at 22^a, the cylinder being suitably formed as at 20^b for the attachment of a feed pipe or the like. The pump is provided at its ends above and 20 below the piston head 23 with inlet and outlet ports 30, 31 and 32, 33 respectively, and by means of which compressed air, steam, or other suitable driving medium may be alternately applied above and below the piston 25 to depress and retract the plunger shaft. This action may be controlled automatically as is well known in the art, and it will be understood that other suitable power means may be employed to reciprocate the plunger. 30 At its lower end the cylinder 20 is provided with a flange 34 extending partially about the circumference thereof and at the ends of the said flange, and occupying the remainder of the circumference, there is provided a flat vertically disposed portion 35 35 extending above and substantially below the lower end of the cylinder and having its inner surface tangential to the bore 21 thereof. The portion 35 has a laterally disposed orifice 36 provided therein, the lower surface thereof being substantially flush with the lower end of the cylinder. The orifice 36 is quite thin in the form shown, while in width it is slightly less than the diameter 40 of the bore 21. These dimensions may of course be varied as desired to suit the particular material being dried, and as shown in Fig. 6, there may be provided a plurality of cylindrical openings, as at 37. The outer 45 end of the orifice extends into a projecting nozzle portion 38 which extends over the end of the drying apron, presently to be described, this portion being shown in cross section in Figs. 5 and 6.

50 The lower end of the bore 21 of the cylinder is closed by a console closure member 39, the lateral portion 40 of which conforms and is bolted as at 41 to the flange 34 of the cylinder, while the depending portion 42 is 55 secured by bolts or screws 43 to the inner

face of the portion 35. The lower surface of the orifice 36, it will be seen, is substantially continuous with the surface of the closure.

At the front face of the portion 35, a circumferential interiorly threaded ring 44 is secured by means of bolts or screws 45, and within this ring 44 there is screwed the exteriorly threaded end 46 of an elongated cylindrical chamber or tunnel 47, which in practice may be of any suitable length to suit the particular drying being carried out. A removable closure is provided at the outer end of the chamber which comprises a plate 48 having an annular threaded ring 49 secured thereto by bolts 50, which is screwed upon the threaded end 51 of the chamber. A removable block 52, preferably formed of hard wood, is disposed in the end of the chamber and has its inner face inclined as at 53 to the edge of an outlet pipe or nipple 54, at the lower end of which there is provided a flange 55 to which may be attached any suitable means for receiving or conveying the dried material.

An inlet pipe 56 and an outlet pipe 57 are provided respectively in proximity to the outer and inner ends of the chamber 47 for the admission of hot air or gas, and flanges 58 and 59 are secured thereto for the attachment of suitable feed and waste connections, and a pressure or vacuum gage 60 is in communication therewith, as at 61. If desired, the chamber may be connected through the pipes 56 and 57 to a vacuum producing apparatus.

Surrounding the major portion of the chamber 47, and preferably intermediate the feed and outlet pipes 56 and 57, there is arranged an annular heating jacket 62, closed at its ends as at 63 and 64, and provided with inlet and outlet pipes 65 and 66, a pressure gage 67 being in communication therewith, as at 68. Within the chamber 47 there is disposed a removable conveyer frame comprising a pair of spaced rectangular side plates 69 and 70, secured together at suitable intervals by means of cross rods 71. These plates are of such height that the frame may be readily withdrawn upon removal of the end closure, and the lower edges thereof rest upon the inner surface of the chamber.

At the outer end of the frame, there is journaled substantially centrally thereof a drive shaft 72 having a drum 73 mounted thereon, one end of the shaft being provided with a retaining collar 74, while the other end is provided with a pinion 75. At the inner end the frame is provided with a pair of superimposed shafts 76 and 77 having guide rollers 78 and 79 mounted thereon, and an endless conveyer or apron 80 preferably formed of canvas, but which may be rubber, metal, or other suitable composition, 130

is carried about these rollers and the drum 73. Intermediate the said rollers and the drum there are provided in suitably spaced relation, a plurality of supporting rollers 82, which maintain the level of the apron. 5 As clearly indicated in Figs. 2 and 3, the ends of the drum and rollers are provided with curved flanges 81 and 82^a which give the apron a basin-shape, thereby retaining 10 the plastic material being dried thereon. At the under side of the apron and in proximity to the ends of the frame, there are provided tightening devices which automatically take up any slack or looseness in the 15 apron. These tightening devices each comprise a yoke member consisting of a pair of arms 83 and 84 connected at the contracted portion thereof by a rod 85 and a sleeve 86, a roller 87 being journaled with- 20 in the enlarged portion, a shaft 88 passing through the said sleeve and secured at its ends to the plate 69 and 70 rotatably supporting the said member. Beneath the yoke member there is mounted upon a shaft 89 a 25 lever arm 90, which bears at one end upon the rod 85 and at its other end is connected to a cross piece 91 by means of a spring 92, thereby yieldably holding the roller in engagement with the apron. The ends of 30 the rollers are rounded as at 93, so that the basin-like shape of the apron is maintained. The small diameter of the rollers 78 and 35 79 permit of the apron extending in flat relation beneath the nozzle 38, while the drum serves to precipitate the dried material into the pipe 54, a doctor or scraping knife 93^a being provided at the outer end of the frame, which removes the material from the apron and forms with the inclined face 40 of the block 52, a chute for the said pipe 54. It will be understood that other suitable means may be employed for removing the material, as for instance, vertical wires 152 in the case of a material which cakes when 45 dried, thus breaking the cake into strips, which renders the removal thereof easier. A bearing support 94 is secured to the chamber 47 by means of rivets 95, and surrounding a shaft opening 96 in the side of 50 the chamber, there is provided on the said support a cup bearing 97 which supports one end of a drive shaft 98 provided within the chamber with a pinion gear 99, and packing 100 is provided within the said bearing 55 to prevent the entrance of air into the chamber, the packing being secured in place by means of a nut 101. The outer end of the shaft is supported in a bearing bracket 102, secured at 103 to an extension 104 of 60 the support 94, and intermediate the said bracket and the nut 101 there are provided upon the shaft a tight pulley 105 and a loose or idler pulley 106 upon which a suitable drive belt may be shifted to operate 65 the shaft.

The pinion gear 99 is so disposed within the chamber, that the pinion 75 of the drum 73 will mesh therewith and be driven thereby when the frame is fully inserted into the chamber. This construction it will be 70 seen, permits of the convenient removal of the frame.

The operation is as follows:

The plunger is raised to the top of its stroke and the cylinder 20 is filled through 75 the opening 20^a with the plastic or semi-liquid material to be dried. A suitable atmospheric state is produced in the chamber 47 which is sealed by the material in the cylinder, and the same is heated by admis- 80 sition of a heating medium, as hot water, steam, oil or the like into the heating jacket. The air in the drying chamber may be of any desirable pressure, either above or below atmosphere, and it may be saturated to any 85 desired degree during the drying of the water of evaporation, or a gas or other suitable composition may be introduced.

The apron 80 is set into motion through the gears 75 and 99, and the plunger 22 is 90 slowly depressed, so that the plastic material is squirted through the orifice 36 in a thin and wide film into the surface of the moving apron, and hence the material will dry quickly and uniformly. The operation is 95 continuous until the material in the cylinder is exhausted, the material drying gradually from the point of injection and deposit upon the apron to the end of the chamber where it is removed and drops through 100 the discharge pipe.

The material when dried may be either in a powdered or caked condition. In either case, the scraper thoroughly removes the same from the apron, and in the latter case, 105 suitable vertical wires 152 may be provided if desired, whereby the cake may be broken into smaller strips, rendering the separation from the apron easier. Should it be desired to dry a material of another color 110 or composition, the conveyer frame may be bodily withdrawn from the chamber by removing the closure at the end thereof, the apron removed from the same, and another apron placed thereon in its stead. The 115 squirting nozzle, plunger, and cylinder are thoroughly cleaned, so that no remnants of the previous dye remain, and thereupon the apparatus is charged with the new dye or chemical which is then dried as above pointed out. The simple construction of the apparatus permits of the easy disassembling thereof for cleaning or other purposes.

It happens, upon occasion, that the material to be dried is in such a moist state that 125 it is desirable to extract the excess moisture before injecting the material into the drying chamber. For this purpose, I provide a filter cap 107, shown in Figs. 7 to 10, which has the same general shape of the closure 130

member 39, and replaces the same as clearly shown in Fig. 8, a piece of filter cloth 108 being placed at the upper side thereof, and held by carrying the same between the flange 110 and the portion 35, as at 108^a. The exposed portion of the upper surface of the filter cap is provided with a plurality of communicating grooves 109, these grooves being preferably formed by two series of spaced parallel V-shaped grooves diagonally crossing each other, so that a studded surface is produced. At that portion of the cap within the bore and removed from the depending flange 110 there are provided a plurality of passages 111, extending entirely through the cap and having their inner ends at the intersection of the grooves. Thus circulation of the moisture is permitted beneath the filter cloth and the same freely runs to and is drained off through the passages 111.

In operation, the orifice 36 is first plugged with material of a greater density than the moist material in the cylinder. The plunger 125 is thereupon forced downwardly pressing the moisture from the material, and as long as the material is soft, the plug seals the orifice and the moisture continues to be drawn off, the filter cloth preventing the material itself from entering the passages 111. As the moisture is removed, the material gradually becomes harder, and the increased pressure upon the plug forces the same out of the orifice whereupon the drying process continues in the normal manner.

In Fig. 11, I have shown a modified apparatus for extracting excess moisture from the material prior to its injection into the drying chamber.

40 The cylinder 120 is provided with a reciprocating plunger shaft 121 within the bore 122 thereof, and with a lateral orifice 123 having its outlet end disposed in the drying chamber 47, as in the foregoing forms.

45 In the lower part of the cylinder, there is provided a piston 124, the piston head 125 of which is disposed in a pressure chamber 126 provided at the lower end of the cylinder. At the uppermost position of the 50 piston indicated in full lines in the drawing, the piston closes the orifice 123, while in its lowermost position which is determined by suitable stops 127 in the pressure chamber, its upper surface is substantially flush 55 with the lower surface of the orifice as indicated in dotted lines.

At a point above the orifice and also above the uppermost position of the piston 124, there is provided in the cylinder a lateral opening 128. A filter member 129 is secured to the cylinder by means of bolts 130, an annulus portion 131 of which is disposed in the said opening 128, and is provided with a plurality of passages 132 extending therethrough, and communicating

70 with a channel 133 of the said member. A filter cloth 134 is secured over the face of the filter, being carried over the sides thereof, as at 135, to securely hold the same. A pipe 136 for carrying off the extracted moisture is secured to the lower end of the filter member.

In operation, pressure is applied below the piston head 125 by any suitable medium, as for instance, steam, or compressed air and the cylinder is filled with the semi-liquid material to be dried. The plunger 121 is thereupon depressed, pressing the moisture from the material, through the filter, the same being carried off through the pipe 136. 80 When the material becomes of the desired consistency, the increased pressure overcomes the pressure in the chamber 126, which it will be understood, is predetermined, depressing the plunger 124 and exposing the 85 orifice 123, whereupon the material is squirted through the orifice into the drying chamber, as before pointed out. The upper end of the plunger 124, it will be noted, forms a base for the bore 122, so that the material 90 is suitably guided into the orifice.

In Fig. 12, I have illustrated the manner of maintaining a vacuum in the drying chamber. The entrance end, as before pointed out, is sealed by the incoming material in the orifice 36, while the pipes 56 and 57 are connected by a manifold 140, to a vacuum pump 141, the ends of the manifold being provided with flanges 142 and 143 respectively, which are secured by bolts 144 to 100 the flanges 58 and 59. Air is thereby exhausted from the drying chamber at both ends.

The delivery pipe 54 has connected thereto a pair of communicating hoppers 145 and 146, the latter being of greater capacity, and each are provided with air tight valves 147 and 148. The hopper 145 is provided with a suitable flange 149 which is secured to the flange 55 by bolts 150, and the hopper 146 110 is provided below the valve 148 with a delivery pipe 151. Normally, during operation of the drier, the valve 147 is open, and the valve 148 is closed, and the hopper 146 becomes filled with the dried material. Thereupon the valve 147 is closed, and upon opening of the valve 148 the material may be removed, the hopper 145 receiving the dried material from the chamber during this removal period. After removal of the material from the hopper 146, the valve 148 is closed and the valve 147 opened. It will thus be seen that a complete vacuum may be maintained in the drying chamber at all times.

125 With my improved process and apparatus it will be seen dyes or other chemicals may be properly dried under vacuum or other atmospheric conditions and the process carried on continuously, tending to the pro- 130

duction of a uniform and perfect product. The simplicity of the apparatus permits of as many apparatuses being used as there are different dyes or chemicals, and on the other hand, an apparatus is provided which by very slight change may be adapted to the drying of different compositions successively.

I have illustrated and described a preferred and satisfactory embodiment of my invention, but it is obvious that changes may be made therein within the spirit and scope thereof, as defined in the appended claims.

I claim:

1. An improved process for drying plastic or semi-liquid compositions which consists in compressing as a whole, a relatively large mass of the material to be dried, and forcing the same by compression in a relatively thin strip unbroken longitudinally through a restricted outlet upon a moving conveyer, and drying the same upon said conveyer.

2. An improved process for drying plastic or semi-liquid compositions which consists in compressing a relatively large mass of material to be dried, expressing excess moisture from said mass by an initial application of said pressure, and squirting said material by subsequent pressure after expression of said excess moisture.

3. An improved process for drying plastic or semi-liquid compositions which consists in compressing, as a whole, a relatively large mass of material to be dried, and squirting said material by compression upon a moving conveyer in a sealed chamber, the incoming material moving at a speed substantially according to the speed of the conveyer, and sealing said chamber at the point of entrance of the material.

4. An improved process for drying plastic or semi-liquid compositions which consists in initially compressing said material to express excess moisture therefrom exteriorly of the drying chamber, providing a yieldable seal in the entrance to the drying chamber, and by continuation of said compression, and when the material has reached a predetermined plasticity, removing said seal by the increased pressure, and squirting the material through a restricted outlet upon a moving conveyer, and drying the same on said conveyer in said drying chamber.

5. An improved process for drying plastic or semi-liquid compositions which consists in causing an extraction of a given quantity of the material from a chamber in a stream unbroken longitudinally upon a moving conveyer, drying the same upon said conveyer, and removing it when dried from said conveyer to a receiving part within said chamber.

6. A drying apparatus for drying plastic or semi-liquid compositions comprising a press having a cavity adapted to receive a

given quantity of material, and having a restricted outlet at one end, a plunger adapted to reciprocate in said cavity to remove said material therefrom through said outlet, a drying chamber in communication with said outlet, a conveyer in said chamber adapted to be continuously operated, said press adapted to squirt the material in a stream unbroken longitudinally upon said conveyer, said plunger adapted to move proportionately to said conveyer, to produce said stream of uniform plasticity and density.

7. A drying apparatus for drying plastic or semi-liquid compositions, comprising a press, having a cavity adapted to receive a given quantity of material, a base for said cavity, said press having an angularly extending outlet passage substantially flush with said base, a plunger adapted to reciprocate in said cavity to remove said material therefrom, a drying chamber in communication with said outlet, a conveyer in said chamber, having its upper surface substantially parallel to said outlet passage, and having one end in proximity thereto, said plunger adapted to compress said material, and cause an angular extraction thereof through said outlet in a stream unbroken longitudinally upon said conveyer.

8. A drying apparatus for drying plastic or semi-liquid compositions, comprising a press, an elongated drying chamber in communication with said press at one end, a removable closure at the other end, means for heating said drying chamber, and a conveyer in said chamber comprising a frame adapted to be bodily removed from said chamber upon removal of said closure, an endless relatively wide conveyer apron carried thereby, and means for continuously driving said apron, said press adapted to continuously squirt the material to be dried upon said apron, said apron adapted to receive the moist material at one end of said chamber and deliver the same dried at the other end thereof.

9. A drying apparatus for drying plastic or semi-liquid compositions, comprising a drying inclosure, a conveyer in said inclosure, comprising a frame, and an endless relatively wide conveyer apron carried thereby, said apron being substantially basin-shaped in cross section, and means for supplying material to be supplied to said conveyer.

10. A drying apparatus for drying plastic or semi-liquid compositions, comprising a press, a closed elongated drying chamber in communication therewith, means for heating said drying chamber, and a conveyer in said chamber comprising a frame, and an endless relatively wide conveyer apron carried thereby, said apron being substantially basin-shaped in cross section.

11. A drying apparatus for drying plastic or semi-liquid compositions, comprising a press, an elongated drying chamber in communication with said press at one end, a removable closure at the other end, means for heating said drying chamber, and a conveyer in said chamber comprising a frame adapted to be bodily removed from said chamber upon removal of said closure, an endless relatively wide conveyer apron carried thereby, and means for continuously driving said apron, said conveyer adapted to be brought respectively into and out of operative relation with said driving means upon insertion and removal of said frame. 5
12. A drying apparatus for drying plastic or semi-liquid compositions, comprising a drying inclosure, a removable closure, a conveyer in said inclosure, adapted to be bodily removed from said chamber upon removal of said closure, an apron carried thereby, means for driving said apron, said conveyer adapted to be brought respectively into and out of operative relation with said driving means upon insertion and removal of said frame. 10
13. A drying apparatus for drying plastic or semi-liquid compositions, comprising a drying inclosure a removable closure, a conveyer in said inclosure, adapted to be bodily removed from said chamber upon removal of said closure, an apron carried thereby, rotatable means for driving said apron journaled in said inclosure, packing means adapted to render the journal air-tight, said conveyer adapted to be brought respectively into and out of operative relation with said driving means upon insertion and removal of said frame. 15
14. A drying apparatus for drying plastic or semi-liquid compositions, comprising a press provided with a discharge orifice, a closed drying chamber in communication with said discharge orifice, a conveyer adapted to be continuously operated in said chamber, a filter for said press adapted to draw excess moisture from said material, and closure means for said orifice adapted to be operated by said press to unseal said orifice, the interposed material between said press and said orifice adapted as the moisture is drawn therefrom to operate said closure means to unseal said orifice, said press adapted to squirt the material to be dried through said orifice upon said conveyer. 20
15. A drying apparatus for drying plastic or semi-liquid compositions, comprising a press provided with a discharge orifice, a drying chamber in communication with said discharge orifice, a filter for said press adapted to draw excess moisture from said material, and closure means under pressure for sealing said orifice adapted to be moved by said press under a pressure greater than the pressure of said closure means. 25
16. In a drying apparatus, feeding means adapted to feed the material to be dried, an elongated drying chamber in communication with said feeding means, a removable closure at one end of said chamber, a conveyer comprising a frame adapted to be bodily removed from said chamber upon removal of said closure, and an endless conveyer apron carried thereby. 70
17. In a drying apparatus, feeding means adapted to feed the material to be dried, an elongated drying chamber in communication with said feeding means, a removable closure at one end of said chamber, a frame adapted to be bodily removed from said chamber upon removal of said closure, an endless conveyer apron carried thereby, and means for continuously driving said apron, said conveyer adapted to be brought respectively into and out of operative relation with said driving means upon insertion and removal of said frame. 75
18. A drying apparatus for drying plastic or semi-liquid compositions, comprising a press having a relatively long angularly disposed discharge orifice of uniform cross section, and a drying chamber in communication with said orifice. 80
19. A drying apparatus for drying plastic or semi-liquid compositions, comprising a press provided with a discharge orifice, a drying chamber in communication with said discharge orifice, a filter for said press, adapted to draw excess moisture from said material, and closure means under pressure for sealing said orifice, adapted to be moved by said press under a pressure of said press, greater than the pressure of said closure means, said closure means adapted to reseal said orifice when said pressure is released. 85
20. A drying apparatus for drying plastic or semi-liquid compositions, comprising a press including two plungers adapted to exert opposed pressure upon material therebetween, a discharge orifice adapted to be closed by one of said plungers, and adapted to be moved to open said orifice when the pressure of the material and said other plunger is greater than the opposed pressure of said plunger, said other plunger adapted to squirt the material through said orifice, and a drying chamber adapted to receive said material. 90
- In testimony that I claim the foregoing as my invention, I have signed my name in presence of two subscribing witnesses.
- CROSBY FIELD.
